(57) CLAIM

The ornamental design for a sports board with bottom rails, as shown and described.

DESCRIPTION

FIG. 1 is a front perspective view of Sports Board With Bottom Rails showing my new design;

FIG. 2 is a top or bottom plan view thereof;

FIG. 3 is a right side elevational view of FIG. 2, the left side being mirror image thereto;

FIG. 4 is a rear elevational view thereof; and,
FIG. 5 is a front elevational view thereof.

The broken line showing of hand holes is for illustrative purposes only and forms no part of the claimed design.
